CONCRETE REINFORCING ACCESSORY

Robert J. Ilukowicz, Coram, N.Y., assignor to
Preco Industries, Ltd., Plainview, N.Y.

Filed May 29, 1975, Ser. No. 581,864

Term of patent 14 years

Int. Cl. D8—08

U.S. Cl. D8—228

FIG. 1

FIG. 2

FIG. 3

FIG. 4

FIG. 5

FIG. 1 is a perspective view of a concrete reinforcing accessory embodying the design of my invention;

FIG. 2 is a top plan view of said concrete reinforcing accessory;

FIG. 3 is a side view of said concrete reinforcing accessory illustrating a side other than that shown in FIG. 1;

FIG. 4 is an end view of said concrete reinforcing accessory illustrating an end other than shown in FIG. 1; and

FIG. 5 is a bottom plan view of said concrete reinforcing accessory.

I claim:

The ornamental design for a concrete reinforcing accessory, substantially as shown.
